UNITED STATES PATENT OFFICE.

SAMUEL W. LAMBETH, OF PHILADELPHIA, PENNSYLVANIA.

FLY-FAN.

SPECIFICATION forming part of Letters Patent No. 234,713, dated November 23, 1880.

Application filed March 20, 1880. (Model.)

To all whom it may concern:

Be it known that I, SAMUEL W. LAMBETH, a citizen of the United States, residing in the city and county of Philadelphia, and State of Pennsylvania, have invented a new and useful Improvement in Fly-Fans, which improvement is fully set forth in the following specification and accompanying drawings, in which—

Figure 1 is a side elevation, partly in section, of the portion of a fly-fan embodying my invention. Fig. 2 is a horizontal section in line α , Fig. 1. Fig. 3 is a horizontal section of a modification.

Similar letters of reference indicate corresponding parts in the several figures.

My invention relates to an improvement in fans which have arms connected to a staff, the rotation whereof is occasioned by a train of gearing, after the manner of clock-work, the motion of the blades which are attached to said arms serving to frighten flies and other insects.

The invention consists in so constructing the rotary staff that its strength is increased, and weight of the device reduced.

Referring to the drawings, A represents a staff or shaft rising from a stand or base, B, containing a mechanical power—such as clock-work—for rotating said staff, as is well known in the class of fly-fans, a vertically-adjustable collar, C, being fitted on said staff and held thereon by suitable means.

The staff or shaft is necessarily long, and, as heretofore constructed of a solid rod, has been broken or found to bend, thus causing difficulty in adjusting the collar and variableness in the rotation of the fan-blades, and it adds considerable weight to the fan. These defects are remedied by my invention, which consists in providing the fan with a hollow or tubular staff, whereby a stronger and lighter fan is produced, the staff preserves its straightness, and the blades rotate regularly, (which otherwise is hurtful to the eyes,) the fan thus being a better and more serviceable article.

I do not claim, broadly, a rotary staff for a fly-fan, as I am aware that that is not new; neither do I claim the fan-supporting collar or mechanism fitted on said shaft, as that is well known; but

What I do claim as new, and desire to secure by Letters Patent, is—

The combination, with the stand B, containing the clock-work, and the collar C, supporting the fan-blades, of the staff A, rising from the stand and connected to the clock-work, and made of tubular form throughout its entire length, substantially as and for the purpose set forth.

SAMUEL W. LAMBETH.
